UNITED STATES PATENT OFFICE.

MICHAEL M. MCINTYRE AND CHARLES F. SCHULTIS, OF CLEVELAND, OHIO, ASSIGNEES.
BY MESNE ASSIGNMENTS, TO THE STANDARD PARTS COMPANY, OF CLEVELAND,
OHIO, A CORPORATION OF OHIO.

CORRECTING-MACHINE.

1,233,680.

Specification of Letters Patent. Patented July 17, 1917.

Application filed August 9, 1915. Serial No. 44,516.

To all whom it may concern:

Be it known that we, MICHAEL M. MCINTYRE and CHARLES F. SCHULTIS, citizens of the United States, residing at Cleveland, 5 in the county of Cuyahoga and State of Ohio, have invented a certain new and useful Improvement in Correcting-Machines, of which the following is a full, clear, and exact description, reference being had to the 10 accompanying drawings.

This invention relates generally to the manufacture of leaf springs and more particularly to a machine for correcting certain defects which sometimes exist in the 15 shaping of the spring.

Occasionally a leaf spring in the course of its manufacture receives a slight lateral curve or twist due to some uneven distribution of metal, or other cause, and the object 20 of the present invention is to provide a simple and efficient machine by means of which such springs can be quickly and easily corrected and brought back to a perfectly shaped spring from end to end without impairing any of the usual qualities of the 25 spring previously imparted thereto, and another object of the invention is to provide a machine of this character which can be quickly and easily adjusted to accommodate 30 different thicknesses of spring, and a still further object is to provide a machine of this character which will be under the control of the operator at all times.

With these objects in view and certain 35 others which will become apparent as the description proceeds, the invention consists in the various novel features of construction and combination hereinafter fully described and pointed out in the claims.

In the drawings forming a part of the 40 specification, we have illustrated one embodiment of our inventive idea, but it will be understood that certain changes and modifications can be made within the scope 45 of the claims without departing from the broad principles of our invention.

Figure 1 is a face view of a machine embodying our invention; Fig. 2 is a side elevation of the same; Fig. 3 is a detail section, 50 partly in elevation, illustrating the shaping or correcting rolls and the manner of supporting and adjusting the upper roll; Fig. 4 is a sectional plan view on the line 4—4

of Fig. 2; Fig. 5 is a section on the line 5—5 of Fig. 2; and Fig. 6 a sectional view 55 on the line 6—6 of Fig. 3.

In the practical embodiment of our invention, we employ a base 10, of suitable size and shape, and mounted thereon are the front and rear upright standards 11 and 12 60 which are connected at their upper ends by suitable tie-rods 13, said standards being suitably spaced by sleeves 14 upon said tie-rods.

A rotary shaft 15 is journaled in the uprights 11 and 12 and is provided with a driving gear 16 on the rear end thereof which gear meshes with a pinion 17, mounted upon the shaft 18 journaled in a bracket 19 bolted to the base, and receiving power 70 from any suitable source such as a pulley or gear.

Spaced above the rotary shaft 15, is a square shaft 21, the forward end of which projects through a rectangular opening in 75 the upright 11, this square shaft being supported and adjusted in a manner herein-after explained.

A shaping or correcting roll 22 is mounted upon the forward end of the square 80 shaft 21, and a mating roll 23 is fixed to the forward end of the rotary shaft 15. The roll 23 is keyed to the forward end of the rotary shaft 15 by a suitable key 24 and is held against longitudinal movement by 85 means of the nut 25 provided with peripheral openings to receive a spanner wrench. The roll 22 is provided with an antifriction bearing 26 in order to reduce friction to a minimum and is held upon the end of the 90 shaft 21 by means of the nut 27.

The rolls 22 and 23 taper rearwardly to accommodate springs which are slightly concaved, as shown, and it will be understood that various shapes of rolls may be 95 employed, dependent upon the cross section of the spring to be corrected.

In order to maintain the fixed shaft and its roll in the proper relative positions and also to provide for easy adjustment, we employ a hanger shaft 30 which is passed transversely through the forward upright 11 and is constructed with an eccentric portion 31, which occupies the open space in said upright, said shaft with eccentric portion being inserted from one side of the up-

right, and a suitable bushing 30^a is provided to compensate for the enlargement of the opening necessary to receive the eccentric portion 31. A two-piece hanger 32 is bolted 5 to the eccentric portion 31, the lower member of said hanger having a depending portion which terminates in a ball 33 which seats in a hemispherical recess 34 produced in the top of the shaft 21, and a sectional 10 ring 35 is placed around the upper portion of said ball and held in place by means of a threaded ring 36 screwed into an internally threaded boss 36^a produced upon the shaft 21, and this ring 36 has an inwardly projecting flange 36^b which overlaps the sectional ring 35 and holds the same in engagement with the ball 33, thereby providing a perfectly secure connection which is capable of universal movement.

20 The shaft 30 carries a graduated washer 37 which is adapted to coact with a pointer 38 arranged upon the upright adjacent to said washer so that the adjustment of the shaft can be graduated, and it will be understood 25 that by turning the shaft 30 one or more degrees in either direction, the shaft 21 and its roll are raised or lowered, by the change in position of the eccentric portion 31 upon which is mounted the hanger supporting 30 said shaft 21.

The shaft 30 is provided with nuts 39 at each end and the projecting end 40 is made square to receive a wrench so that said shaft can be adjusted and then held fixed while 35 the nuts 39 are being tightened up to secure the shaft in its adjusted position.

The shaft 21 has a cross-pin 28, the ends of which are trunnioned in plates 29 sliding in the recessed portion of the upright 12 and 40 these plates are held in position during such movements by means of the overlapping strips 29^a secured to the forward face of the upright 12. This arrangement permits the square shaft 21 to be adjusted vertically 45 so as to move the roll 22 toward or away from the driving roll 23 carried upon the rotary shaft 15.

For the purpose of raising and lowering the square shaft 21, we employ toggle arms 50 41 which are pivotally connected at their upper ends to the shaft 21 and at their lower ends are connected to toggle arms 42, the lower ends of said arms being pivotally connected to a bracket 42^a projecting forwardly 55 from the upright 12. At the knuckle or joint of the toggle arms 41 and 42, we connect a toggle link 43 which is also connected to a bell crank 44 pivoted in a bracket 45, formed upon the upright 11, said bell crank 60 being operated by a pull rod 46 which is divided as shown at 47 and connected at its lower ends to the foot treadle 48; a coil spring 49 being interposed between a fixed bracket and a collar upon the pull rod for 65 the purpose of lifting the same and break-

ing the toggle when the foot treadle is released, it being obvious that by pressing down upon the foot treadle the toggle is straightened, which raises the rear end of the square shaft 21 and throws the forward 70 end carrying the roll 23, down toward the rotary shaft with its roll so as to bind upon the leaf spring 50 which has previously been placed between the opposed portions of the rolls 22 and 23; the shaft 21 rocking or 75 vibrating upon the ball 33 of the depending hanger, there being just sufficient movement of the shaft 21 to bring the roll 22 into proper position with reference to the roll 23 and move the same out again after the 80 operation has been completed.

The engagement of the rolls 22 and 23 upon the leaf spring 50 causes the spring to travel along between the rolls while being subjected to pressure and in this manner the 85 spring is straightened or corrected or reshaped so that when a spring which is slightly curved or twisted or bent is passed between the rolls from one end to the other, it emerges from between the rolls a perfectly 90 straightened or corrected spring with the metal properly distributed to produce the best results.

In order to maintain the spring perfectly true while traveling between the rolls, we 95 provide a face plate 51 fastened to the forward upright 11 and against which the spring bears, and in order to provide against undue wear of this face plate, we arrange hardened steel rollers 52 at oppositely disposed points in the plate 51 and against which the spring bears upon opposite sides of the rolls 22 and 23 as most clearly shown in Fig. 1, suitable openings 53 being produced in the face plate to permit insertion 105 of the hard steel rollers 52. These rollers receive the wear or friction incidental to the travel of the spring, and thus save the wear or friction upon the face plate.

A machine constructed as herein shown 110 and described, has been found highly efficient for the correction of the defects hereinbefore referred to, and in addition to its simplicity and durability, is exceedingly quick and easy in operation.

Having thus described our invention, what we claim is:—

1. In a machine of the character described, the combination with a contact plate having an opening therein, of a pair of rolls 120 operating within said opening, the plane of said plate being at right angles to the axes of said rolls when in operative position and in alinement with the rear portions of said rolls.

2. In a machine of the kind described, the combination with a rotary shaft having a roll fixed thereon, of a non-rotatable shaft having a roll movable thereon, and a contact plate arranged in a plane at right angles 120

- to the axes of said rolls, said plate being in alinement with the rear portions of said rolls and adapted to serve as a bearing plate upon opposite sides of said rolls.
5. In a machine of the character described, the combination with a rotary shaft having a roll fixed thereon, of an adjustable vibratory shaft having a roll rotating thereon and adapted to coöperate with the first mentioned roll, and a bearing surface arranged at right angles to the axes of said rolls.
4. In a machine of the character described, the combination with a rotary shaft having a roll fixed thereto, and means for operating said shaft, of a shaft arranged in substantially parallel relation to the rotary shaft, means for adjusting the position of said second shaft, means for vibrating the same transversely, and a roll adapted to turn upon the end of said second shaft, said roll being adapted to coöperate with the roll fixed upon the rotary shaft.
5. In a machine of the kind described, the combination with a pair of rolls adapted to feed a strip of metal therebetween, of a contact surface arranged in a plane at right angles to the axes of said rolls, said contacting surface being in alinement with the rear portions of said rolls and upon opposite sides of said rolls.
6. In a machine of the character described, the combination with a rotary shaft having a roll fixed thereon, and means for operating said shaft, of a shaft suspended intermediate its ends and having a roll rotating upon the end of said shaft, said roll being adapted to coöperate with the roll upon the rotary shaft, means for vibrating said suspended shaft, means for adjusting the point of suspension, and a bearing surface arranged at right angles to the axes of said rolls.
7. In a machine of the character described, the combination with a rotary shaft and means for operating the same, and a roll fixed upon the forward end of said shaft, of a second shaft spaced above the rotary shaft and substantially parallel therewith, a roll rotating upon the forward end of said second shaft, an adjustable hanger for suspending said second shaft intermediate its ends, operating means for vibrating said second shaft together with means for maintaining said shaft in its normal position.
8. In a machine of the character described, the combination with a rotary shaft and means for rotating the same, said shaft having a roll fixed upon the forward end thereof, of a second shaft spaced above the rotary shaft and a roll rotating upon the forward end of said shaft, a suspending shaft, an adjustable hanger arranged thereon, and adapted to suspend said second shaft intermediate its ends, toggle arms connected
- to said second shaft adjacent its rear end together with means for operating said toggle arms to vibrate said second shaft, for the purposes specified.
9. In a machine of the character described, the combination with a rotary shaft having a roll fixed upon its forward end, and means for rotating said shaft, of a second shaft spaced above the rotary shaft and having a roll rotating upon its forward end, a hanger for suspending said second shaft, an adjustable suspending shaft upon which said hanger is mounted, toggle arms connected with said second shaft and means for operating toggle-arms, and a bearing surface arranged at right angles to the axes of the rolls as set forth.
10. In a machine of the kind described, the combination with a pair of rolls adapted to feed a strip of metal therebetween, of anti-friction rolls arranged upon opposite sides of said rolls, and means for carrying said anti-friction rolls, the surfaces of said anti-friction rolls being at right angles to the axes of said strip feeding rolls.
11. In a machine of the character described, the combination with a pair of rolls, of a contacting plate arranged at right angles to the axes of said rolls, and oppositely disposed bearing rolls mounted within the contacting plate as set forth, said plate being in alinement with the rear portions of said rolls.
12. In a machine of the character described, the combination with a rotary shaft and a roll thereon of a second shaft having a roll loosely mounted thereon, a suspending shaft having an eccentric portion, a hanger mounted upon said eccentric portion and having a depending portion terminating in a ball, means for universally connecting said ball and second shaft, together with means for vibrating said second shaft.
13. In a machine of the character described, the combination with a rotary shaft carrying a roll, of a non-rotatable shaft spaced above the rotary shaft and having a roll movable upon its forward end, means for suspending said upper shaft, and means for raising and lowering the roll upon said shaft by vibrating said shaft.
14. In a machine of the character described, the combination with a rotary shaft having a roll at its end, of a non-rotatable shaft spaced above the rotary shaft, a roll movable upon its forward end, an adjustable hanger shaft, a hanger thereon universally connected to said spaced shaft, and means connected to said shaft for vibrating the same, whereby the movable roll is moved toward and away from the roll on the rotary shaft.
15. In a machine of the character described, the combination with a rotary shaft carrying a roll, of a non-rotatable shaft

spaced above the rotary shaft and having a roll movable upon its forward end, means for suspending said upper shaft, means for raising and lowering the roll upon said shaft by vibrating said shaft, and a contacting plate arranged at right angles to the axes of the rolls and in alinement with the rear portions of said rolls.

16. In a machine of the character described, the combination with a rotary shaft having a roll at its end, of a non-rotatable shaft spaced above the rotary shaft, a roll movable upon its forward end, an adjustable hanger shaft, a hanger thereon universally connected to said spaced shaft, and means connected to said shaft for vibrating the same, whereby the movable roll is moved toward and away from the roll on the rotary shaft, of said rolls.

17. In a machine of the kind described, the combination with a pair of rolls adapted to feed a strip of metal therebetween, of bearing surfaces upon opposite sides of said rolls and in a plane at right angles to the

axes of said rolls and in alinement with the rear portions of said rolls.

18. In a machine of the character described, the combination with a plate having an opening therein, of a pair of rolls arranged in said opening, the plane of said plate being at right angles to the axes of said rolls, the surface of said plate being so positioned with reference to said rolls that a strip of metal passed between said rolls will contact with said plate, and bearing rollers arranged in said plate upon opposite sides of said rolls, the outer surface of said rollers being substantially flush with the face of said plate and in alinement with the rear portions of said rolls.

In testimony whereof, we hereunto affix our signatures in the presence of two witnesses.

MICHAEL M. MCINTYRE.
CHARLES F. SCHULTIS.
